APPARATUS FOR MOUNTING GEMS

Filed April 17, 1923

2 Sheets-Sheet 2

UNITED STATES PATENT OFFICE.

SAMUEL TOY, OF BOSTON, MASSACHUSETTS.

APPARATUS FOR MOUNTING GEMS.

Application filed April 17, 1923. Serial No. 632,795.

To all whom it may concern:

Be it known that I, SAMUEL TOY, a citizen of the United States, residing at Boston, county of Suffolk, Commonwealth of Massachusetts, have invented certain new and useful Improvements in Apparatus for Mounting Gems, of which the following is a specification.

My present invention involves an improvement in gem setting and the like and more particularly to a novel method of and apparatus for mounting a gem or the like in a pronged jewelry setting.

There are at present various types of such pronged mountings used in a variety of articles of jewelry and these different types are in turn formed in a variety of shapes to receive stones of different contours and cuttings, some of which are symmetrical and some of which are unsymmetrical. Various attempts have been made to improve the method and means for mounting said stones in such settings, but such have usually involved radial pressure which has had a tendency to crack or crush the stone or else was not adapted or adaptable to different styles, shapes and sizes.

In accordance with my invention I proceed upon a different principle which in brief consists in forming for any desired commercial setting an arbitrary seat of predetermined contour, in placing the stone on such a seat and in then turning in the prong tips above the seat simultaneously and continuously by a gradual pressure applied substantially vertically of the prongs, but so as to get a resultant progressively effective in planes of a corresponding diminishing contour.

As illustrative of my invention I will show herein somewhat diagrammatically my method of setting and will also show the tool which I have found well adapted to its purpose and one capable of such production as would enable it to be available to the average jeweler. Throughout the specification and drawings like reference characters are employed to indicate corresponding parts, and in the drawings:

Fig. 1 is a side elevation of a tool in accordance with my invention.

Fig. 2 an end view of the same.

Fig. 3 a view in plan.

Fig. 4 an enlarged side view partly broken and partly in section.

Fig. 4^a a detail view of the seat former and holder.

Fig. 5 a view of the prong closer and its holder.

Fig. 6 a face view of such a closer.

Fig. 7 a detail of the prong spreader.

Figs. 8 and 9 diagrammatically illustrate a prong setting before and after the seat forming operation.

Fig. 8^a diagrammatically illustrates three steps in the seat forming operation.

Figs. 10 and 12 are face views of modified forms of prong closers.

Figs. 11 and 13 sectional views, on lines 11—11 of Fig. 10 and 13—13 of Fig. 12, respectively, of the same.

Fig. 14 is a diagrammatic illustration of the closing operation, and

Fig. 15 a further diagrammatic illustration of the relation of the seat forming and closing operations by a comparison of their devices.

In considering my invention it should first be understood that in its usual application it deals ordinarily with a symmetrical prong mounting of one of the well known types, as for example, such as is illustrated in Fig. 8. Such a mounting M has its prongs P extending generally in the direction of its longitudinal diameter. The prongs P are capable of being bent and usually have to be more or less bent for stones of intermediate size and frequently have to be trued up in the case of symmetrical settings in order to restore symmetry which has been lost through accidental bending.

In accordance with my invention I form on the inner faces of these prongs P seats S. This is preferably accomplished by a seat forming tool 1. This is also preferably a rotary tool comprising for the case shown a conical point terminating in a cylindrical base and is in its general character in the nature of a fine tooth cutter or burr, although it also preferably has a slight spinning action by which the prongs P are expanded slightly if necessary.

The diameter of the cylindrical portion of the tool 1 as well also as the angularity of its conical portion is sized on average 103 sizes of gem stones or their artificial imitations so that the seat S is given not only the proper diameter but the proper flare so as to receive with as accurate a fit as possible, some facet against which the adjacent prong 110

may gain substantial bearing. Incidentally with symmetrically cut stones there would be substantial uniformity.

The first operation in accordance with my invention is therefore the formation of a seat of predetermined configuration when considered in the transverse plane. The supplementary step may perhaps best be considered in its broader aspects with reference to Fig. 14. Here I have indicated a gem G, a prong P of the setting and in full lines a partial section of a prong closer 2. The actual face view of this prong closure is seen in Fig. 6 in which case it is a simple 15 conical concavity which has the following relation to the seat former 1:

Referring to Fig. 15, it will be seen that the seat former 1 if considered for example, in the plane which constitutes the base of its conical portion, has a circular configuration of a diameter which finds its corresponding diameter in the plane y—y at the left of Fig. 15. In this figure, the closing device is diagrammatically illustrated at 2 25 in what would be a central section, at the left of the view, while at the right of the view the lines x—x are projected through the corresponding face view.

The prong closer 2 therefore may be considered as being made up of a surface or surfaces which would show in a series of horizontal cross sections the configuration of the predetermined seat in a diminishing series. In the simple form illustrated in Fig. 6 which is a conic, the contour of the action is circular. In the form shown in Fig. 10, which is really in effect an octahedral, the sections are correspondingly octagonal. In the form of Fig. 12, which 40 might be considered as the curvilinear equivalent of the same, the sections are generally oval.

It will therefore be understood that the inner face of the concave prong closure may 45 consist of planes of curved surfaces, it only being necessary that there be a substantial preservation of the configuration of successive sections and the successive diminution in their area.

Returning to Fig. 14 it will be seen that if the prong P is properly supported with the gem G on its seat S and the closer 2 be advanced in the vertical axis of the same, the prong tips P will be gradually turned 55 over to a position P' shown in dotted lines in which they are laid firmly against any adjacent portions or facets of the gem G and all without any direct transverse radial pressure.

The apparatus illustrated herein is especially designed for a jeweler or smaller shops and is at once convenient and efficient. It comprises a head 10 having an upper member 11 and a lower member 12 which 65 is carried up to form an outwardly pro-

jecting jaw 13 which corresponds with a jaw 14 fast on the member 10. The lower portion 12 and the parts carried by it, as may best be seen in Fig. 4, are adjustable vertically of the main frame 10 by a screw 70 15 turned by an enlarged knurled head 16, which also constitutes a base or support for the frame when the tool is rested on the bench.

Mounted on an extension of the portion 75 12 are a pair of clamping jaws 17 tightened by a milled head screw 18. The jaws 17 are mounted on the stem of the screw 18 and are adapted to receive any setting, as for example, the ring R while being acted on by the seat former 1.

On the jaws 13 which constitute an expansion holder for the ring R or similar device, is a stop 19 adjusted by a screw 20 turned by a milled nut 21. Through both 85 jaws I form a vertical opening, as 28, in which any shank, as of an ear ring, may be passed while the article is thus supported.

In the upper extension 11 at the top of the frame 10, I mount a threaded spindle guide 90 22 which is tapped through the frame 11 and turned by a milled head 23. Within this is a spindle 24 which may be rotated by a hand wheel 25. At its lower end the spindle 24 has a chuck 26 within which anyone of a series of detachable and replaceable seat formers 1 may be held. Through the frame 11 is a bushing 30 within which is guided a slide 31 having a head 32 and normally sustained by a spring 33. The 100 slide 31 has threaded to its lower end a socket 34 constituting a part of a detachable and replaceable prong closer 2. As before explained, these prong closers are recessed members of special interior surface 105 and related to the seat former 1 as regards its configuration on certain planes.

In the form shown I provide the head 10 with a handle 40 and pivoted thereto at 41 I provide a finger lever 42 having a bent 110 end 43 adapted to bear on the head 32 of the slide 31. In using the tool to make a simple conventional setting as for example, in a ring R, the ring is clamped between the jaws 17, see Figs. 4 and 4^a, in proper alignment to the spindle 24 and rotated by the hand wheel 25 to form the seat S as illustrated in Fig. 8^a. As suggested above, sometimes one prong of a setting will be bent out of place or the prongs will require a 115 little more spread. I provide in convenient position on the lower frame 12 a detachable removable spreader 27 over which the prongs may be pressed to secure a preliminary spread, as indicated in Fig. 7. This 120 spreader consists of a simple plug, the shank of which is simply received within a hole in the member 12 (see Fig. 4), the frictional engagement of the spreader shank with the 125 wall of the hole being sufficient to fix the 130

spreader against accidental displacement. The ring having its seat so formed is transferred to the jaws 13 and 14 over which the ring is slipped. The setting is now centered by turning the knurled screw 21 until the feeler 35 is in the center of the stone. This feeler 35 is a very small spring pressed pin projecting in the vertical axis of the prong closer. It is held down by a very light 10 spring 36 and not only serves as a guide in centering the stone but holds the stone in its seat while the closer is descending upon the prongs. Before the closer is actually brought into contact with the prongs the 15 jaws 13 and 14 are expanded by rotation of the milled base 16 to firmly hold the ring in position. The operating handle 42 is now pulled to bring the closer down over the jaws. In order to prevent the closer from 20 traveling too far down I provide under the operating end 43 of the finger lever 42 a stop screw 50 which has a thumb nut 51 having a scale edge (see Fig. 4) which can be turned with reference to a pointer 53 25 so that just the amount of closing may be effected. In accordance with my method and with such a device, stones may be set or reset very rapidly and very securely and with a very small amount of breakage.

30 Various modification in mechanism and certain modifications in the method may be made all without departing from the spirit of my invention and if within the limits of the appended claims are to be each considered as a part of my invention as fully 35 as they would if herein described in detail.

What I therefore claim and desire to secure by Letters Patent is:

1. In a gem mounting device for pronged 40 settings, a seat former of predetermined configuration in a plane transversely thereof and a recessed reciprocable prong closer having its interior walls continuously inclined and including in successive planes trans- 45 versely of it, the said predetermined configuration of the seat former and means for supporting a pronged setting with its seat coaxially of the recess of the prong closer.

2. In a gem mounting device for pronged 50 settings, a detachable, replaceable seat former of predetermined configuration in a plane transversely thereof and a detachable replaceable recessed reciprocable prong closer having its interior walls continuously in- 55 clined and including in successive planes transversely of it, the said predetermined configuration of the seat former and means for supporting a pronged setting with its seat coaxially of the recess of the prong closer.

60 3. In a gem mounting device for pronged jewelry settings, a seat former operative to produce a predetermined seat configuration in a plane transversely of the vertical axis of the setting and a recessed recipro-

cable prong closer having its interior walls continuously inclined and including in successive planes transversely of it the said predetermined configuration of the seat former in diminishing relation and means for supporting a pronged setting with its seat coaxially of the recess of the prong closer. 70

4. An instrument for mounting gems or the like in pronged settings consisting of a head, a rotatable spindle mounted therein, an oppositely disposed clamp substantially aligned therewith, means for rotating and feeding the spindle, a tool chuck on the end of said spindle, a reciprocable slide carried by one member and operatively disposed for movement towards the other member, a support on said other member in substantial alignment with said slide and a detachable replaceable forming device mounted on the end of said slide and having a recess in its lower face of predetermined configuration and having an inclined inner surface outwardly and downwardly flaring at an angle to the vertical through the gem receiving seat portion of each prong of a predetermined pronged jewelry setting. 75 80 85 90

5. An instrument for mounting gems or the like in pronged settings consisting of a head comprising a pair of bracket members, a rotatable spindle mounted in one member and having an oppositely disposed clamp mounted in the other and substantially aligned therewith, means for rotating and feeding the spindle, a tool chuck on the end of said spindle, a reciprocable slide carried by one member and operatively disposed for movement towards the other member, an externally expanding clamp disposed on said other member in substantial alignment with said slide and a detachable replaceable forming device mounted on the end of said slide and having a recess in its lower face of predetermined configuration and having an inclined inner surface outwardly and downwardly flaring at an angle to the vertical through the gem receiving seat portion of each prong of a predetermined pronged jewelry setting. 95 100 105 110 115

6. A hand tool for mounting gems or the like in pronged settings consisting of a head comprising a pair of bracket members, a handle thereon, a rotatable spindle mounted in one member and having an oppositely disposed clamp mounted in the other and substantially aligned therewith, means for rotating and feeding the spindle, a tool chuck on the end of said spindle, a reciprocable slide carried by one member and operatively disposed for movement towards the other member, a cooperating lever member pivoted to said head and having one end engaging said slide and the other in finger engaging relation to said handle, an externally expanding clamp disposed on said head in substantial alignment with said slide 120 125 130

and a detachable replaceable forming device mounted on the end of said slide and having a recess in its lower face of predetermined configuration and having an inclined inner surface outwardly and downwardly flaring at an angle to the vertical through the gem receiving seat portion of each prong of a predetermined pronged jewelry setting.

7. A hand tool for mounting gems or the like in pronged settings consisting of a head comprising a pair of bracket members, an adjustable foot therefor, a handle thereon, a rotatable spindle mounted in one member and having an oppositely disposed clamp mounted in the other and substantially alined therewith, means for rotating and feeding the spindle, a tool chuck on the end of said spindle, a reciprocable slide carried by one member and operatively disposed for movement towards the other member, a cooperating lever member pivoted to said head and having one end engaging said slide and the other in finger engaging relation to said handle, an adjustable stop for said lever, an externally expanding clamp disposed on said head in substantial alinement with said slide and a detachable replaceable forming device mounted on the end of said slide and having a recess in its lower face of predetermined configuration and having an inclined inner surface outwardly and downwardly flaring at an angle to the vertical through the gem receiving seat portion of each prong of a predetermined pronged jewelry setting.

8. A hand tool for mounting gems or the like in pronged settings consisting of a head, a rotatable spindle mounted thereon and an oppositely disposed clamp substantially alined therewith, means for rotating and feeding the spindle, a tool chuck on the end of said spindle, a second clamp, a reciprocable slide carried by the head and operatively disposed for movement thereto, means for reciprocating the slide, an adjustable stop for said reciprocating means

and a detachable replaceable forming device mounted on the end of said slide and having a recess in its lower face of predetermined configuration and having an inclined inner surface outwardly and downwardly flaring at an angle to the vertical through the gem receiving seat portion of each.

9. A hand tool for mounting gems or the like in pronged settings consisting of a head comprising a rotatable seat former of predetermined form, a jewelry mount support substantially alined therewith, means for rotating and feeding the seat former, a reciprocable slide carried by one member and operatively disposed for movement towards the other member, and a forming device having a recess in its lower face of predetermined configuration with respect to said seat former and having an inclined inner surface outwardly and downwardly flaring at an angle to the vertical through the gem receiving seat portion of each prong of a predetermined pronged jewelry setting.

10. A hand tool for mounting gems or the like in pronged settings consisting of a head comprising a rotatable detachable and replaceable seat former of predetermined form, a jewelry mount support substantially alined therewith, means for rotating and feeding the seat former, a reciprocable slide carried by one member and operatively disposed for movement towards the other member, and a detachable replaceable forming device having a recess in its lower face of predetermined configuration with respect to said seat former and having an inclined inner surface outwardly and downwardly flaring at an angle to the vertical through the gem receiving seat portion of each prong of a predetermined pronged jewelry setting.

In testimony whereof I affix my signature.

SAMUEL TOY.
